STOCKING

George W. Senior, Ephrata, Pa., assignor to Millway Knitting Mill, Inc., Millway, Pa., a corporation of Pennsylvania

Application November 5, 1951, Serial No. 17,281

Term of patent 14 years

(Cl. D47—7)

To all whom it may concern:

Be it known that I, George W. Senior, a citizen of the United States, residing at Ephrata, county of Lancaster, State of Pennsylvania, have invented a new, original, and ornamental Design for Stocking, of which the following is a specification, reference being had to the accompanying drawing, forming a part hereof.

Fig. 1 is a side elevational view of a stocking embodying the said design.

Fig. 2 is a fragmentary rear perspective view of the same.

I claim:

The ornamental design for a stocking, as shown.

GEORGE W. SENIOR.
